(57) **CLAIM**

The ornamental design for a pot cover, as shown and described.

DESCRIPTION

FIG. 1 is a perspective view of the pot cover of our design; FIG. 2 is a front elevational view of the pot cover, it being understood that the rear elevational view is the same;

FIG. 3 is a right side elevational view of the pot cover shown in FIGS. 1 and 2, it being understood that the left side elevational view is the same;

FIG. 4 is a top plan view of the pot cover; and,

FIG. 5 is a bottom plan view of the pot cover.

The broken line showing of a pot cover is included for the purpose of illustrating environmental structure and forms no part of the claimed design.
